CLAIM

The ornamental design for a handsfree device for a handset, as shown and described.

DESCRIPTION

FIG. 1 is a perspective front view of a handsfree device for a handset showing my new design;

FIG. 2 is a perspective review thereof;

FIG. 3 is a front view thereof;

FIG. 4 is a rear view thereof;

FIG. 5 is a bottom plan view thereof;

FIG. 6 is a top plan view thereof;

FIG. 7 is a perspective front view of the handsfree device of FIGS. 1-6 in an alternative in-use position; and,

FIG. 8 is a rear perspective view thereof.
